DELIVERING MEANS FOR PRINTING
MACHINES

Thomas C. Maley, Dayton, Ohio, assignor to
Ohmer Fare Register Company, Dayton, Ohio,
a corporation of New York

Application March 16, 1927. Serial No. 175,862

9 Claims. (Cl. 164—49)

This invention relates to an improved delivering means for tickets, receipts and the like after they have been printed and severed.

One of the objects of the invention is to provide a movable means interposed between the severing means and the exit opening so that instruments such as knives and screwdrivers may not be inserted through the exit opening into the path of movement of the severing means. Sometimes operators desire to render such a machine inoperative. With my improved structure they cannot render it inoperative by inserting any tool into the knife or severing mechanism or into other movable parts of the machine.

Another object of the invention is to provide a delivering means which will operate in time relation to the printing means, the feeding means and the severing means.

In the drawing:

Fig. 1 is a front fragmentary elevational view of the machine.

Fig. 2 is a side elevational view showing the main driving shaft and associated parts in the position in which they would be when the main driving shaft has made one-half a revolution.

Fig. 3 is a cross-sectional view showing the parts in the position in which they would be after the machine has been operated, and

Fig. 4 is a side elevational view of the knife operating mechanism.

This invention is an improvement on the application of Albert S. Wheelbarger and Grover C. Coil, Serial No. 65,532, filed October 29, 1925 and issued May 17, 1932 as Patent No. 1,858,813, to which patent reference is made for a more complete disclosure of the machine as a whole. The subject matter of this invention may, however, be incorporated in any machine designed to print and issue tickets, coupons, receipts and the like.

Referring more particularly to the drawing, a counter shaft 1 is provided with a manually operated crank 2 and a gear 3 which meshes with and drives a gear 4, which drives a shaft 5 and a disk 6. The disk 6 is in fact a mutilated gear having gear teeth 7 on a portion of its circumference which teeth drive a pinion 8 secured to a shaft 9. The pinion 8 has one short tooth which lies behind the disk 6 so that the two adjacent teeth form a locking engagement with the periphery of the disk 6. The end teeth of the gear teeth 7 are elongated so as to engage the short tooth of the pinion 8, all of which structure is described in detail in the said application No. 65,532. The pinion 8 drives a pinion

10 secured to a shaft 11. The shaft 9 is provided with an impression roller 12 while the shaft 11 is provided with an electroplate 13, between which roller and electroplate the ticket strip 14 passes. The disk 6 is provided with a wrist pin 15 which actuates a pitman 16 attached to a lever 17 by means of a stud 18. The stud 18 is attached to an oscillating printing carrier 19 fulcrumed on a shaft 20 and provided with platens 21 and 22 and an ink roller 23.

The main drive shaft 5 is provided with a cam 24 which actuates a bell crank lever 25 pivoted on a shaft 26, which bell crank lever actuates a movable knife blade 27 which is caused to travel upwardly against a fixed knife blade 28, severing the paper strip after it has been printed.

The main shaft 5 is also provided with two cams 29 which engage the fingers 30 of a lever 31 pivoted on a shaft 32. A spring 33 is secured to the shaft 32 and at its other end abuts against a pin 34 on the lever 31, thereby tending to hold the levers 31 in the position shown in Fig. 3. The levers 31 are connected at their upper ends with a delivering means 35 which is rectangular in vertical cross-section, but whose upper and lower walls converge toward each other at the outer end so as to substantially conform to the sides of the exit opening 36 in the casting 37. A spring baffle plate 38 is secured to the lower wall of the delivering means and extends upwardly, resiliently pressing against the lower surface of the upper wall and thence extending slightly downwardly again.

The latter portion of the movable knife 27 is provided with a U-shaped hook 43 which receives a knob 49 of the bell crank lever 50, pivoted on a pin 51 secured to a plate 52, mounted on a shaft 5 and cross-bar 32. The other end of the bell crank lever 50 is provided with an offset lug 53 which projects into the path of movement of the cam 54, rigidly secured to the rotatable shaft 5 and bell crank lever 55 is pivoted on cross-bar 32. One arm of the bell crank lever 55 is provided with a cam surface 56 which is engaged by the said cam 54. The other arm of the bell crank 55 is provided with a cam lug 57 which engages the lower beveled edge 58 of the lug 53. Under the cam 57 is a recess 59 to receive the lug 53, and a second arm of the bell crank lever 55 terminates in a cam portion 60. The parts are normally in the position shown in Fig. 4, at which time the crank handle 2 has not commenced its rotation. As the crank handle 2 is rotated, the shaft 5 is rotated thereby. The cam 54 is in engagement with the cam surface

56. As the cam 54 rotates in a counter-clockwise direction, as viewed in Fig. 4, it rotates the bell crank lever 55 in a clockwise direction, so that cam 57 engages the lower bevel surface 58 of the lug 53, rotating the bell crank lever 53 clockwise, and lowering the movable knife 27. The movable knife is now held in its lowered position by the lug 53 engaging the forward side of the recess 59. As the cam 54 continues this 10 rotation, it engages the cam portion 60 of the bell crank lever 55, rotating the lever 55 in a counter-clockwise direction, and thereby lowering the forward edge of the recess 59 below the lug 53. The cam 54 now engages the lug 53, 15 rotating the bell crank lever 50 in a counter-clockwise direction, and raising the knife, thereby severing the paper. When the cam 54 has passed the lug 53, it engages for a second time the cam surface 56, rotating the bell crank lever 20 55 in a clockwise direction, so that the cam 57 again engages the bevel surface 58 of the lug 53, thereby slightly rotating the bell crank lever 50 in a clockwise direction and lowering the knife into its normal position as shown in Fig. 4.
- 25 It is necessary to lower the knife as last described so that in case the paper 14 has been completely consumed, a new roll could be inserted. If the movable knife closed the opening between the knife blades, it would be impossible 30 to insert a new roll of paper.
- Before the agent commences the operation of the machine the parts are in the position shown in Fig. 3. In operation the agent rotates the crank 2 clockwise, moving the printing carrier 35 19 rearwardly so that the ink roller 23 is brought beneath the type wheels 39 and the platen 22 is then moved beneath the type wheels 39 pressing the paper strip 14 against the same. The gear teeth 7 now engage the teeth of the pinion 8, rotating the pinions 3 and 10, feeding the ticket strip forward and impressing thereon the printed matter carried by the electroplate 13, which has been inked by the ink roller 40. The cam 24 thereafter engages the bell crank lever 40 45 25 moving the movable knife plate 27 upwardly, thereby severing the paper. As soon as the operator commences the rotation of the crank 2 thereby rotating the main drive shaft 5 the cam 29 has moved the delivering means 35 from the 50 position shown in Fig. 3 to that shown in Fig. 2. The rollers 12 and 13, therefore, feed the ticket strip above the spring baffle 38, and when the knife 27 moves upwardly severing the paper, the ticket is securely held between the upper surface of the spring baffle 38 and the lower surface 55 of the upper plate of the delivering means 35. The upward movement of the knife 27 does not displace the delivering means 35, for a cutaway portion 41 is provided in the rear end of the 60 delivering means which cutaway portion is of a configuration conforming to the shape of the upper part of the knife. Immediately prior to the completion of the operation of the machine the nose of the cam 29 has passed the finger 30, 65 and the spring 33 now moves the delivering means from the position shown in Fig. 2 to that shown in Fig. 3, so that the forward end of the delivering means is now exactly adjacent the exit opening 36.
- 70 It will be noted that when the delivering means 35 is in the position shown in Fig. 2 it would be impossible to insert any instrument through the opening 36 and between the knife blades 27 and 28. It would likewise be impossible in 75 any other position in which the delivering

means 35 might be. I therefore provide an improved delivering means and at the same time provide means to prevent the insertion of an object such as a screwdriver for the purpose of damaging or mutilating the machine.

I realize that many changes may be made in the specific form which I have shown herein without departing from the spirit of this invention. I desire, however, to claim the invention broadly in whatever form it might be embodied which may fairly fall within the terms of the appended claims.

I claim:

1. In a machine of the type described, paper feeding and severing means, a holding and delivery means for the severed sections, and means whereby said holding and delivery means is first moved towards said feeding means to receive one of the severed sections and is then moved away from said feeding means to deliver it, and means whereby the feeding and severing means are held inoperative while the holding and delivery means is being moved away from the feeding means.

2. In a machine of the type described, a casing, paper feeding and severing means within said casing, said casing having a discharge opening in a different horizontal plane from the severing means, a delivery means for the severed sections of paper also arranged within said casing, and means for moving the delivery means from the receiving relation with said severing means into discharge relation with said opening.

3. In a machine of the type described, paper feeding means, severing means for the paper, a delivery means for the severed sections, a combination baffle and holding means carried by said delivery means, and means whereby said paper severing and feeding means are operated in timed relation then held stationary and means whereby the delivery means is operated while the severing and feeding means are held stationary.

4. In a machine of the type described, a casing provided with an exit opening, paper feeding means, a severing means, the cutting edge of which is in a different horizontal plane from the exit opening, a delivery and holding means, and means for moving the delivery and holding means away from the feeding means upon the actuation of the feeding and severing means.

5. In a machine of the type described, a casing provided with an exit opening, a paper feeding means within said casing, a knife located above and behind said exit opening, a delivery and holding means, and means for moving the delivery and holding means away from the feeding and severing means upon the operation of the said feeding and severing means.

6. In a machine of the type described, a casing provided with an exit opening, a paper feeding means, a severing means having its cutting edge in a different horizontal plane from the exit opening, a delivery means, and means whereby said delivery means is moved back and forth between said severing means and said exit opening.

7. In a machine of the type described, a casing provided with an exit opening, a paper severing means, the cutting edge of which is in a different horizontal plane from the exit opening, a delivery means, and means whereby said delivery means is moved so as to receive a severed section of the paper and is there-

after actuated so as to deliver said severed section to the exit opening.

8. In a machine of the type described, a casing provided with an exit opening, a paper severing means, the cutting edge of which is in a different horizontal plane from the exit opening, a receiving and holding means, and means whereby said receiving and holding means is moved towards said cutting means to receive a 5 section of said paper and is thereafter moved 10 adjacent said exit opening to deliver said severed section.

9. In a machine of the type described, a cas-

ing, paper feeding and severing means within said casing, said casing having a discharge opening located in a different horizontal plane from the severing means, the severing means being located between the said opening and the feeding means, a delivery means for the severed sections of paper, and means for moving the delivery means adjacent the severing means to receive a severed section of paper and to move said delivery means into discharge relation with 85 said opening.
